(57) CLAIM

The ornamental design for an intense pulsed light epilator, as shown and described.

DESCRIPTION

FIG. 1 is a top, front and right side perspective view of an intense pulsed light epilator, showing my new design;
FIG. 2 is a bottom, rear, left side perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof; and,
FIG. 9 is another top, front and right side perspective view of the intense pulsed light epilator showing a use state where a top cover is taken off.
The broken lines illustrate portions of the intense pulsed light epilator as shown and described.
